CLAIM

The ornamental design for a combined flipper switch and four-way switch, as shown and described.

DESCRIPTION

FIG. 1 is an isometric view of a combined flipper switch and four-way switch showing my new design;

FIG. 2 is a top plan view; and,

FIG. 3 is a front elevational view, the rear, left side and right side elevations being identical in appearance to the front elevation.

The bottom of the combined flipper switch and four-way switch forms no part of the claimed design.
